UNITED STATES PATENT OFFICE.

JAMES C. WOODSON, OF EAST PITTSBURGH, PENNSYLVANIA, ASSIGNOR TO WESTINGHOUSE ELECTRIC & MANUFACTURING COMPANY, A CORPORATION OF PENNSYLVANIA.

OVEN.

Application filed December 18, 1922. Serial No. 606,599.

To all whom it may concern:

Be it known that I, JAMES C. WOODSON, a citizen of the United States, and a resident of East Pittsburgh, in the county of Allegheny and State of Pennsylvania, have invented a new and useful Improvement in Ovens, of which the following is a specification.

My invention relates to ovens and particularly to ventilated ovens.

One object of my invention is to provide a relatively simple construction for an oven, comprising inside and outside skeleton frames and a plurality of heat insulating 15 wall panels held thereby.

Another object of my invention is to provide an electrically heated oven with means for removing heavy gases produced by japanned or enameled objects placed therein, while maintaining a flow of air through the oven that shall insure a substantially even temperature throughout the oven chamber.

In practicing my invention, I provide an 25 inside skeleton frame comprising angle bars and members of channel section, against which is held a plurality of heat-insulating panels enclosing an oven chamber. A plurality of electric heating elements are located 30 at the sides of the oven chamber substantially co-extensive therewith. A solid protecting baffle is located at the outside of the heating elements, extending from the floor upwardly for a portion of the height of the 35 heating elements, and a perforated baffle or screen extends upwardly therefrom and over the top of the heating elements. A perforated inlet air-conduit is located beneath each of the sets of heating elements adjacent the 40 side walls of the oven. One end of each of the conduits extends outwardly through the rear panel, where it may be connected to a blower pipe or to the atmosphere. An outlet air-conduit, having side perforations 45 only, is located on the floor centrally and longitudinally of the oven chamber and is connected to the suction pipe of the blower.

In the accompanying drawings,

Figure 1 is a view, in side elevation with 50 certain portions of the furnace structure cut

away, of an oven embodying my invention,

Fig. 2 is a top plan view thereof,

Fig. 3 is a view, in rear elevation thereof, with a part thereof cut away, and

Fig. 4 is a fragmentary sectional view to 55 illustrate the construction and arrangement of the bottom and side panels.

An oven 11, which is here illustrated is substantially rectangular in shape, comprises a plurality of top panels 12, rear panels 13, 60 floor panels 14 and side panels 15, all of these being heat-insulating panels, of substantially the same general construction. Each panel comprises an outer sheet metal wall 16, and an inner sheet metal wall 17, 65 located in spaced relation, the space therebetween being filled with a quantity 18 of a suitable heat-insulating material, such as mineral wool. Any suitable or desired construction to hold the sheet metal plates 16 70 and 17 may be employed and I have indicated, in Fig. 4, of the drawings, one of the methods which may be employed and which comprises providing each of the plates with laterally extending and co-operating flange 75 portions.

The bottom panels 14 are provided with laterally extending members 19, of channel section, located between and suitably secured to the sheet metal plates 16 and 17, as substantially the entire weight of the rest of the oven structure is carried by these panels. The bottom sheet metal plate 16 extends beyond the edge of the panel and is provided with a small upturned flange portion 21, the 80 construction forming a member of channel section, into which the lower edge of the side panels 15 extend in order to provide an interlock between the side and the bottom panels.

An inner skeleton frame work comprises longitudinally extending angle bars 22 located at the top and the bottom edges of the side panels and vertically extending angle bars 23 at each side of the oven, gusset plates 95 24 being employed to secure the members together. Horizontally and laterally extending angle bars 25 have their ends secured to the angle bars 22 and 23 by the same gusset plates 24. The bottom members 100

of the inner skeleton frame work are constituted by members 26 of channel section which extend horizontally and laterally of the oven and which are suitably connected 5 to the respective members 22 and 23 by gusset plates 27.

The hereinbefore described construction of 10 longitudinally extending angle bars, the vertically, and the horizontally and laterally 15 extending angle bars and the members of channel section constitute an open skeleton frame work substantially rectangular in contour against which the respective top, side and end panels may be located.

15 Means for holding the plurality of panels against the inner skeleton frame work comprise an outer skeleton frame work built up of longitudinally extending angle bar members 28 located at the top and at the bottom 20 of the panels and connected by a plurality of laterally extending angle bars 29 located at the top and bottom, the respective ends of which are connected by gusset plates 31 to the angle bars 28. At the bottom a plurality 25 of members 32, of channel section, are suitably secured by bolts 33 to the members 26, the bottom panels 14 being located and clamped therebetween. At the front, a pair 30 of heat-insulating door panels 34 are provided with suitable hinge members 35 to permit of their being opened and closed as required by the operation of the oven.

In building up the oven structure comprising 35 the inner and the outer skeleton frame work and the plurality of heat-insulating panels, the members 32 of channel section are first placed upon a level floor surface in proper spaced relation relatively to each other, after which the floor panels 14 are located thereon. Then the inner skeleton 40 frame work, as hereinbefore described, is built upon the floor panels, after which the side, rear and top panels may be placed in their proper operative positions against the inner skeleton frame work. Then the outer 45 skeleton frame work is built up and placed in its proper operative position on the outside of the heat-insulating panels after which the door panels 34 may be placed in their proper operative position. The entire 50 structure provides an oven which is substantially air tight.

A plurality of electrical heating elements 55 36 and 37 are located in superposed positions adjacent to the side walls of the oven, each of the heating elements being substantially co-extensive with the wall of the chamber. The heating elements 36 and 37 may be of any suitable or desired construction, but preferably 60 embody a suitable metal frame work upon which a resistor member is insulatedly mounted, the frame work being secured against the vertically extending angle bars 23 by suitable angle members 38. I employ 65 preferably relatively high and narrow

heating elements in order that the amount of space occupied thereby at each side of the oven chamber may be as small as possible to provide a maximum possible space within the oven for receiving work or material to 70 be heat treated.

A perforated air-inlet conduit 39 coextensive with the oven chamber is located under each of the heating elements 37 and comprises a sheet metal duct substantially square 75 in lateral section, which is provided with a plurality of perforations 41 in its upper surface, the perforations extending along the entire length of the member 39. A sheet metal baffle plate 42 is provided adjacent to 80 the outside surface of the heating elements 36 and 37 and has its lower edge operatively engaging the upper surface of the conduit 39. The baffle plate 42 extends upwardly 85 along the outside of the heating elements for at least one half of their height and a perforated baffle or screen 43 extends to the top of the heating element and thereover against the side of the oven to protect the heating elements against damage by reason 90 of objects falling thereon. The conduit 39 has its front end closed and its rear end extending outwardly through the rear panel 13 so that air may enter the duct.

An outlet air duct 44, substantially rectangular in section and relatively wide and flat, is located within the oven chamber centrally thereof and extends longitudinally from the front of the oven structure to the rear thereof and through a suitable opening 100 in the back panel 13 to the outside atmosphere.

Suitable clamping means 45 are provided to secure the outlet duct in its proper operative position on the floor of the furnace. A plurality of perforations 46 are provided 105 in the side walls of the duct 44 and extend over substantially its entire length, through which air and gases are withdrawn from the oven chamber.

A blower 47 is mounted on a suitable supporting means 48 on the top of the oven structure and may be driven by a suitable electric motor 49. The structure 48 may comprise an enclosed sheet metal casing to which one end of a plurality of conduits 51 may be connected, the other end of each of which is suitably connected to the projecting end of the air inlet conduits 39. A conduit 52 has one of its ends connected to the projecting end of the outlet conduit 44 and has its other end connected to the blower 47. If desired, the blower may be provided with an exhaust conduit 53 connected to the casing 48, the amount of air which may leave therethrough being regulated by a damper having an operating lever 54. If it is considered desirable to provide for either a forced circulation or a recirculation of air through the oven cham- 110 115 120 125 130

ber, the lower end of the conduits 51 may be connected to a portion only of the conduit 39, the other portion being open to the atmosphere.

- 5 If the blower is operated with the exhaust conduit open, heated air is withdrawn from the oven chamber through the outlet conduit 44 and is forced through the exhaust conduit into the outer air. Only a 10 relatively small portion of the heated air from the chamber will be forced through the inlet conduits 51 and 39 back into the oven chamber, and therefore cold fresh air enters through the open portion of the conduit 39, to be heated by the heating elements 37 and 38 to be exhausted through the outlet conduit. This method therefore provides for a circulation of air through the oven chamber. 15
- 20 If a recirculation of air is desired, the damper 54 is closed, and the heated air is withdrawn from the furnace chamber through the outlet conduit 44 and is then forced by the blower through the inlet conduits 51 and 39 back into the oven chamber. If the conduit 39 is partly open to the outer air, a small quantity of fresh cold air is, of course, drawn into the oven chamber, but if this is undesirable, such opening 25 may be closed.
- An oven of this type is more particularly intended for use in drying enameled or japanned metal articles which are placed within the oven chamber mounted on suitable 30 carriages adapted to hold the work with the least possible contact therewith. During the drying of such enameled or japanned metal articles, gases are produced which are heavier than air and these will flow or move 35 downwardly and rest upon the floor of the oven chamber. The hereinbefore described construction, comprising air inlet conduits which force the incoming air to flow past the vertically extending heating elements 40 which are enclosed over substantially the greater portion of their height, provides means for insuring that the incoming air shall flow upwardly into the furnace chamber before starting on its outward path. 45
- 50 With the hereinbefore described construction of heating elements and of the co-operating cold air inlets, the heavier-than-air gases hereinbefore described as being produced by the japanned articles will gather 55 more particularly in the central portion of the chamber immediately above the floor thereof from which place they will be quickly removed through the outlet duct hereinbefore described.
- 60 The device embodying my invention thus provides a positive means for insuring a substantially uniform temperature throughout the oven chamber and for causing substantially all of the volume of the chamber 65 to be traversed by incoming heated air.

Various modifications and changes in detail and arrangement may be made without departing from the spirit and scope of the invention, and such modifications are intended to be covered by the appended 70 claims.

I claim as my invention:

1. In an oven, in combination, a skeleton frame-work, a plurality of heat-insulated panels secured to said frame-work and enclosing an oven chamber, and electric heating elements supported by said frame-work adjacent the bottom of the sides of said furnace chamber. 75

2. In an oven, in combination, a skeleton frame-work, a plurality of heat-insulated panels secured to said frame-work and enclosing an oven chamber, electric heating elements supported by said frame-work adjacent the bottom of the sides of said furnace chamber, and air inlets for said oven located below said heating elements. 80

3. In an oven, in combination, a skeleton frame-work, a plurality of heat-insulated panels secured to said frame-work and enclosing an oven chamber, electric heating elements supported by said frame-work adjacent the bottom of the sides of said furnace chamber, air inlets for said oven located below said heating elements and an air outlet located on the floor of said oven and between said air inlets. 90

4. In an oven, in combination, a skeleton frame-work, a plurality of heat-insulated panels secured to said frame-work and enclosing an oven chamber, electric heating elements supported by said frame-work adjacent the bottom of the sides of said furnace chamber, air inlets for said oven located below said heating elements and an air outlet located on the floor of said oven and between said air inlets, said air inlets and outlets being substantially co-extensive with the length of said furnace chamber. 105

5. In an oven, in combination, a skeleton frame-work, a plurality of heat-insulated panels secured to said frame-work and enclosing an oven chamber, electric heating elements supported by said frame work adjacent the bottom of the sides of said furnace chamber, air inlets under said heating elements substantially co-extensive therewith, and means adjacent said heating elements for deflecting the incoming air upwardly past said heating elements. 110

6. In an oven, in combination, an extended oven chamber, air inlets at the sides of said oven chamber, an air outlet in the middle of said oven chamber, and means for causing a positive circulation of air through said chamber from each side upwardly toward the middle of the chamber and then downwardly to the outlet. 115

7. In an oven in combination, an extended oven chamber, air inlets at the sides of 120

said oven chamber, an air outlet in the middle of said oven chamber, said inlets and outlet being substantially co-extensive with the length of said chamber.

5. 8. In an oven in combination, an extended oven chamber, air inlets at the sides of said oven chamber, an air outlet in the middle of said oven chamber, means for causing a positive circulation of air through said

chamber from each side upwardly toward the middle of the chamber and then downwardly to the outlet and electric heating means located above said inlets for heating the incoming air.

In testimony whereof, I have hereunto 15 subscribed my name this 27th day of November 1922.

JAMES C. WOODSON.
